ATTORNEY

UNITED STATES PATENT OFFICE.

THOMAS L. PHILLIPS, OF AURORA, ILLINOIS.

WATER-HEATER.

SPECIFICATION forming part of Letters Patent No. 707,349, dated August 19, 1902.

Application filed March 3, 1902. Serial No. 96,530. (No model.)

To all whom it may concern:

Be it known that I, THOMAS L. PHILLIPS, a citizen of the United States, residing at Aurora, in the county of Kane and State of Illinois, have invented certain new and useful Improvements in Water-Heaters, of which the following is a specification.

My invention relates to improvements in apparatus for heating water, especially adapted for use in connection with a system of heating buildings by the circulation of hot water through continuous pipes and suitable radiators.

The special object of my improvements is to produce a water-heater in which the water is exposed to the heat given off by incandescent coals instead of that given by flame, in which the water is caused to circulate through a pipe placed in the hottest part of the fire-bed, in which the water is exposed to the maximum area of heating-surface, and in which all the heat units produced in the fire-bed will be utilized to heat water before they escape through the chimney or smoke-stack.

A further object of my invention is to provide a water-heater in which the desired results may be attained by keeping down the draft to a point sufficient only to keep the coals red, thus avoiding the wasteful results incident to maintaining a flame for heating purposes, as is common in water-heaters in general use.

Having the foregoing objects and others of general utility in view, I have produced the heater hereinafter described, and which is illustrated in the accompanying drawings, which form part of this application.

In said drawings, Figure 1 is a vertical section through my improved water-heater. Fig. 2 is an elevation of the same, and Fig. 3 is a cross-section on the line $\alpha\alpha$ of Fig. 1.

Referring to the drawings in detail, A represents the base of my improved heater, in which are included the ash-pan a' ; the ash-box a^2 , and a plate a^3 . Secured in any suitable manner to the inner periphery of the plate a^3 are lugs a^4 , which serve as supports for a circular grate B. The grate is formed with a central opening b^3 and is adapted to be rocked in a horizontal plane and to be tilted for dumping purposes. Any preferred or well-

known means for rocking and dumping the grate may be adopted, the same forming no part of my invention, and therefore not shown.

Supported upon and secured to the plate a^3 , with a water-tight joint therebetween, is a cylindrical fire-box or magazine C, the vertical diameter of which is approximately three times its horizontal or cross diameter, thus forming a long narrow fire-box. Surrounding the fire-box and spaced therefrom is a casting or jacket D, the lower edge of which is secured to the plate a^3 . The annular chamber between the jacket and the walls of the fire-box is adapted to hold water to be heated by the radiation from the fire-box in the usual manner.

The walls of the jacket are perforated near the top to receive one end of a pipe d' and are also perforated near the bottom on opposite sides to receive the ends of the pipes d^2 and d^3 . The pipe d' is connected directly or indirectly with the pipe E above the heater, as indicated by dotted lines in Fig. 1. Connected with the pipe d^3 is a pipe d^4 , which passes through an opening in the walls of the ash-box below the grate and has its inner end coupled by a suitable elbow with the pipe E, which passes upwardly through the opening b' in the grate, through the fire-box, and has its upper end connected with the heating-pipes in the system.

The fire-box and jacket are covered by a plate F, in the center of which is an opening to permit the passage of the pipe E. Said plate is also formed with a suitable opening and collar f' for a smoke-pipe and is provided with a hopper e' , through which fuel is placed in the fire-box, said hopper being of any desired form and constituting no part of this invention.

The pipe d^2 connects with the return-pipes of the heating system, which lead from the connections of the pipe E in the usual manner, thus completing the circuit.

It will be noted that by providing a contracted fire-box with relatively great vertical diameter and filling same with fuel I secure a combustion-chamber in which the oxygen drawn through the grate is caused to traverse a long distance, during which it is brought into intimate contact with the fuel, before it

escapes up the chimney. By extending the pipe E throughout the entire length of the fire-box and in the center thereof I surround it with a deep bed of red coals, the heat from which comes into intimate contact with the walls of said pipe, which walls also serve as a flue or conduit for the drafts of oxygen which enter through the opening b' in the grate. As the column of oxygen passes upward along the walls of the pipe E it is met by and mingles with the carbon from the fuel, thus producing a high degree of heat around said pipe. The fire-box may be partially or entirely filled with fuel, the depth of the fire-bed determining the volume of heat to which the water will be subjected.

I am aware that water-heaters have been constructed with a central fire-box and an annular water-chamber or jacket thereabout and that in some instances water-pipes have extended into the fire-box above the fire-bed, where they are subjected to the heat generated within the fire-box, and I therefore do not claim such constructions; but

25 What I claim as new, and desire to obtain by Letters Patent, is—

1. A water-heater comprising a vertical, narrow fire-box, a grate at the bottom of the fire-box, and a water-conducting pipe extending from the center of the grate throughout the entire length of the fire-box and in the center thereof, substantially as set forth.

2. A water-heater comprising a long, narrow, vertical fire-box, a grate at the bottom of said box, and a water-conducting pipe extending upwardly through said grate, and

throughout the entire length of the fire-box, as set forth.

3. A water-heater comprising a fire-box, a water-chamber surrounding said box, a pipe 40 communicating with said chamber, passing through the grate from below, and extending throughout the entire length of said fire-box and in the center thereof, as set forth.

4. In a water-heater, a vertical fire-box narrow in cross-section and adapted to be entirely filled with fuel, a water chamber or jacket surrounding the fire-box, a water-pipe communicating with said chamber and passing throughout the entire length of the fire-box and in the center thereof, said pipe and chamber communicating with a system of water-pipes and radiators substantially as set forth.

5. In a water-heater, a vertical fire-box, narrow in cross-section and provided at the top with means for introducing fuel, at the bottom with a grate and ash-pan, and without openings in its sides; a water-chamber surrounding the fire-box, and water-conducting 60 pipe communicating with said chamber, passing under said grate and up through the center thereof, and extending throughout the length of the fire-box, for the purpose described.

65 In testimony whereof I affix my signature in presence of two witnesses.

THOMAS L. PHILLIPS.
